WATCHMAN'S RECORDING SYSTEM

Lesley Kennedy, Lake Forest, and Alois Beyer,
Chicago, Ill., assignors to Detex Watchclock
Corporation, New York, N. Y., a corporation of
Delaware

Application September 11, 1935, Serial No. 40,082

12 Claims. (Cl. 234—39)

This invention relates to a system for obtaining a record of a watchman's round or rounds of duty, and it has among its objects to provide a watchman's recording system in connection with which a watchman is provided with a portable recording unit containing a record upon which a complete record of his tour or tours of inspection may be obtained, including records of the various stations visited and records of times 5 visited certain designated stations which have associated therewith time controlled keys for making time indications upon the same record which shows the stations visited.

Another object is to provide a compact portable recording unit for use in conjunction with different station and time recording keys, which does not contain any time clock mechanism or other mechanism capable of being disturbed or maladjusted by either wrongful intent or negligent handling.

Another object is to provide a record strip and record strip feeding mechanism whereby records of time and of stations visited may be recorded in series relation for an indefinite number of 25 consecutive tours of duty.

Another object is to provide, in a recording unit having means for receiving a recording key and a record receiving paper to be impressed or imprinted upon by the recording key, a locking device for preventing the insertion of the recording key at all times except when the cover of the recording unit is completely closed, whereby untimely tampering with the recording mechanism or record is impossible and no record can 35 be made except when the cover is closed.

Another object of the invention is to provide a novel time recording key and time controlled mechanism for operating the same.

Other objects involving novel constructions 40 and combinations of parts will appear in the specification and claims thereof setting forth what is now considered to be the best mode of applying the invention. This may be fully understood from the detailed description and drawings in which:

Fig. 1 is a front elevation of the time recording key and associated clock mechanism.

Fig. 2 is a side elevation of the recording key and clock mechanism illustrated in Fig. 1.

Fig. 3 is an enlarged front elevation of the time recording key illustrated in Fig. 1 with parts broken away for illustrative purposes.

Fig. 4 is a section on line 4—4 of Fig. 3.

Fig. 5 is a section on line 5—5 of Fig. 4.

Fig. 6 is an enlarged partial view of the time controlling mechanism illustrated in Fig. 1.

Fig. 7 is a side elevation of the time controlling mechanism illustrated in Fig. 6.

Fig. 8 is a detail view taken on line 8—8 of Fig. 6.

Fig. 9 is another detail view taken on line 9—9 of Fig. 6.

Fig. 10 is a view of the time cam and lever arm just prior to the dropping of the arm.

Fig. 11 is an enlarged perspective view of the stepped crown element which controls the recording of time.

Fig. 12 is a plan of the watchman's portable recording unit with the cover raised.

Fig. 13 is an elevational view on line 13—13 of Fig. 12.

Fig. 14 is a view similar to Fig. 12, with the record and other elements removed or broken away for showing understructure.

Fig. 15 is a section on line 15—15 of Fig. 14.

Fig. 16 is a section on line 16—16 of Fig. 14, which is on the transverse line of printing.

Fig. 17 is an enlarged view of recording mechanism on the transverse line of printing.

Fig. 18 is an enlarged elevational view taken on the transverse line of printing.

Fig. 19 illustrates principal parts of a station recording key.

In the watchman's recording system of the present invention the watchman is provided with a portable recording unit containing a record strip which is automatically advanced each time a record is made thereon at designated stations which the watchman must visit during his rounds of inspection. Station keys are provided at these designated stations, each key having a station character thereon identifying the station visited.

The order of visits at the respective stations is indicated upon the record strip by the staggered series of entries thereon. The staggering of the station records is automatically taken care of by mechanism within the recording unit which causes longitudinal advance of the record strip each time a station recording key is used for making a record and by the lateral displacement effected because of the different positions of the printing dies on different station keys. The system contemplates the use of clock mechanism for obtaining a time record upon the record strip contained in the watchman's portable recording unit. There may be one or more time controlling units placed at desired stations along the route a watchman is to inspect. The time unit may be placed either at the beginning or end of

15

a tour of inspection or at or between any selected stations, and the watchman is required to make a time record in the recording unit which he carries by inserting therein a time recording key which is under the control of the time unit. This time recording key is shaped differently from the station recording key and a socket or guide means suitable for receiving the same is provided in the portable recording unit. The use of timing mechanism independent of the portable recording unit makes it possible to vary the location of the timing unit in reference to the regular recording stations which a watchman is required to visit, and also makes it possible to vary the periods of time during which the time recording key will control the recording of a given time so that changes may be made unknown to the watchman and beyond his control.

In the drawings, and particularly in Figs. 1, 2, 3, 4 and 11, we have illustrated a time recording key 10 contained in a box or housing 11 which has a removable cover 12, whereby the recording key is accessible to the watchman for recording purposes. The time controlled element 13 is rotated by a shaft 14 under the control of clock mechanism 15 contained in a casing 16. The housing 11 and casing 16 are connected by a tube 17 and the clock mechanism is completely enclosed so that unauthorized access to all mechanism contained therein, save only the business end of the recording key, is impossible of attainment. The casing of the clock mechanism is preferably covered with a door 18 by which all parts of the clock mechanism may be kept unseen as well as inaccessible. Suitable locks are provided for all compartments with their keys available at a supervisor's office.

The time recording element 13 of the time recording key is a stepped crown provided in the present instance with twelve steps, each corresponding to one hour of time, so that for every twelve hours, the stepped crown will make one complete revolution. The rate of rotation or the number of steps upon the stepped crown may be varied for obtaining records of time indications for shorter or longer periods of time. For example, if one-half hour periods were used the number of steps would be doubled for the same rate of rotation of the crown.

The stepped member 13 is mounted for rotation upon a stem 20, journaled at 21 in the key support 22. Key support 22 provides a bearing 23 for a sleeve member 24 to which the stepped crown member 13 is keyed at 25. The member 24 carries a pinion 26 engaging another pinion 27 carried by a shaft 28 mounted in bearings contained in the upper portion of the recording key housing 11. The recording key support 22 is pivotally mounted at 29 in line with the line of contact between pinions 26 and 27 so that the recording key may be swung from within its housing to the position illustrated in Fig. 4 for enabling the watchman to engage the same with the portable recording unit which he carries without disengaging the driving connection. A spring 30 is provided for swinging the recording key outward from its housing when the cover is removed, and replacement of cover 12 causes the recording key to be restored to its housing, as illustrated in Fig. 2.

The stepped crown is enclosed within an outer casing 32, with which it is permitted to slide longitudinally of the key support 22 by means of pin and slot connections 33. A spring 34 which continually urges the casing outwardly is seated

at one end of the bearing socket in support 22. A collar 35 is secured to casing 32 and serves as an abutment for the other end of spring 34 and as an abutment for the shoulder 36 of stepped crown member 13, so that when the key is applied to the portable recording unit spring 34 will absorb whatever shock may be transmitted to the stepped crown member. Sleeve 32 is provided with a pair of pins 42, which engage in complementary slots 43, 43, in socket or guide member 44 (Fig. 16) of the watchman's portable recording unit for the purpose of alining slot 45 (Figs. 3 and 4) in sleeve 32 of the time recording key with the operating element 46 (Fig. 16) of the time recording means. This causes the time recording mechanism to be set up in accordance with the particular step of the stepped crown which is opposite slot 45 in a manner to be described hereafter.

The function of the stepped crown 13 is to set recording indicia in the watchman's portable recording unit. The recording of an indication corresponding to the step of the stepped crown 13 is brought about by the use of stem 20 which engages an actuating lever 124 (Fig. 16) contained in the watchman's portable unit and which will hereinafter be described. The recording key is so constructed that any shock resulting from contact of the end of the stem 20 with the actuating lever is taken up by a spring 38 (Figs. 3 and 4) normally compressed between a shoulder 39 of the support 22 and a collar 40 upon stem 20. The stem is otherwise free to move longitudinally of the recording key. It will be observed that the construction of the time recording key is such as to discourage and even prevent tampering therewith. To this end the mounting of the key is protected by a guard member 48 and a shield 49 so that pinions 26, 27, and associated shafts 28 and 14, are out of reach.

Having reference to Figs. 1, 2, 6, 7, 8, 9 and 10, the upper end of shaft 14 is connected to a short shaft 52 supported by a bracket 53. This shaft carries an indicator wheel 54 having indicia corresponding with the various steps upon the stepped crown 13. Shaft 52 is under the control of cam 54 and lever 55. Cam 54 is mounted upon the hour hand arbor of clock mechanism 15 and is so designated that it will raise lever 55 uniformly and permit it to drop once for each revolution of the cam. Lever 55 is mounted upon a bearing pin 56 and its lower end has a finger 57 engaging a rocking member 58. This latter member is mounted for oscillation about shaft 52 and it carries a pawl 59 which engages ratchet wheel 60 to advance shaft 52 each time lever 55 is permitted to fall by the passage of the high part 61 of the cam from under the lever. Clockwise rotation of cam 54 causes the upper end of the lever 55 to be raised and the lower end of the lever 57 to move from its right-hand position (Figs. 6 and 8) to its left-hand position (Fig. 9), and when the upper end of the lever is permitted to fall, spring 62 draws the lower end 57 of the lever and moves member 58 from its left-hand position (Fig. 9) to its right-hand position (Figs. 6 and 8), thereby causing pawl 59 to rotate ratchet wheel 60. Ratchet wheel 60 is pinned to shaft 52 and its rotation causes rotation of shaft 14 and of stepped crown 13, as previously described.

Pawl 66 is a spring-pressed pawl having a spring 67 which urges the pawl against the teeth of ratchet wheel 60 and thereby serves as a safety stop against the reverse rotation of shaft 52.

Also fixed to shaft 52 and forming part of ratchet wheel 60 is another ratchet wheel 64 (Figs. 7 and 8) which is engaged by a locking pawl 65. Pawl 65 carries a pin 68 in engagement with a slot 69 in rocker plate 58. The relationship of the slot and pin is such that the pawl is maintained out of locking position except at the moment when the shaft has completed its forward rotation under the advancing action of rocker plate 58 and pawl 59, at which moment pawl 65 is brought into engagement with ratchet wheel 64 to lock the ratchet wheel and shaft against overrunning.

A quick acting device is provided for prompt and precise restoration of all time controlled parts to their initial positions. This device is provided at the upper end of lever 55 and includes a roller 71 and a triangular support therefor 72. The support is pivoted upon lever 55 at 73, and it has a flanged edge 74 for limiting its movement about the pin. When cam 54 is acting upon lever 55 through roller 71 support 72 assumes the position illustrated in Fig. 10 with flange 74 limiting its anti-clockwise movement. When roller 71 reaches the crest of the high point 61 of the cam it will quickly kick out and rotate support member 72 clockwise thereby permitting lever 55 to fall to the low part of cam 54, under the action of spring 62, as illustrated in Fig. 6. This action rotates the stepped crown 13 of the time recording key to starting position.

The portable recording unit is illustrated in Figs. 12 to 18, inclusive. This unit includes a casing or container 80 which completely encloses its contents and prevents access thereto except by the proper recording keys which are used to produce the desired records. The casing is provided with a cover 81 having a lock so as to prevent access to the contents except by an authorized person. As has been already explained, a key or socket member 44 is provided in the lower part of the casing for receiving the time recording key. In the present instance, the bore of the socket is round to accommodate the particular key which has been described, but the form is not of the essence, it being merely preferable that the socket be different from that provided for the station recording keys, so the watchman may not be confused or have any excuse for not having made a proper record at any particular station. Immediately above socket 44 there is another socket or guide means 83 for receiving a station key 84 which will be described hereinafter. The cross-sectional form of the station key is rectangular and the guide means 85 within the casing is likewise rectangular for accommodating the key (Fig. 16).

The portable recording unit is provided with a record sheet and means for advancing the same step by step. The record sheet preferably is in the nature of a paper strip wound into a supply roll 86 (Fig. 14). The supply roll is mounted at one end of the casing and an advancing drum 87 is mounted at the other end of the casing. The supply roll may be mounted in any convenient manner, as on a pin supported by a pair of uprights and held in place by spring-pressed arms, as illustrated in Figs. 14 and 15. The record 88 is threaded through slot 89 and passes through spaces 90, 91 at either side of the station key guide means 85, over plate 92 and onto drum 87. The record is provided with holes 93 along both of its longitudinal edges and these are engaged by teeth 94 on the advancing drum. A keeper 108 (Fig. 12) holds the record strip in place

against the drum. The paper is permitted to coil upon and store itself in the space below the advancing drum.

The paper is advanced each time a station recording key is used to impress a record upon the record strip. The mechanism for advancing the record includes a lever 95 having one end disposed within the station recording guide means 85 so that when the key is introduced in the guide means it will cause rocking of lever 95 about its pivot 96 (Fig. 14). Lever 95 engages an arm 97 pivoted at 98, which is in continual engagement with the lower end 99 of lever 100, which is mounted upon pin 101. When the recording key is inserted in guide means 85 it will contact with lever 95 and cause lever 100 to rock counterclockwise (Fig. 15) and carry with it link 102, which has a pin and a slot connection 103 with an arm 104. Arm 104 is mounted to oscillate about the bearing pin of drum 87, and after it has been displaced counterclockwise by the action just described, it will be restored to its position of rest by the action of spring 105. Arm 104 carries a spring-pressed pawl 106 which engages the teeth on wheel 107 for actuating the drum to which it is attached. The action of the spring causes clockwise rotation of arm 104 and paper feed when lever 95 is permitted to return to its normal position upon the withdrawal of the station recording key from its guide means 85.

By arranging the record advancing means to advance the record each time a station key is used, each character printed by a station key will be displaced longitudinally of the record for an interval corresponding to the length of advance 35 of the record, and, as illustrated in Fig. 17, when different station indicia are used, as for example 1, 2, 3 and 4, they will appear in staggered and serial relation to each other. The staggered relation will be an uninterrupted straight diagonal 40 line, but if the stations are visited in improper order, the station visited out of turn will be recorded off of the straight diagonal, with the result that any irregularity in the watchman's inspection as to both station and sequence of visits 45 will be immediately apparent.

It is desirable to cause advance of the record strip when the cover is raised or lowered. For accomplishing this, a member 109 is secured to the cover (Fig. 15). This member 109 depends 50 into the casing and has two edges 110 and 111 by which the record strip advancing drum may be actuated upon the closing and opening movements of the cover. When the cover is closed, edge 110 engages projection 112 on lever 100 55 (Figs. 14 and 15), and when the cover is raised, edge 111 engages the same projection and likewise causes rocking of lever 100. Thus, from either opening or closing of the cover, arm 104 is rocked anti-clockwise (Fig. 15) and then released for 60 an advancing movement of drum 87 and accompanying feed of the record.

As explained hereinbefore, the time recording key is provided with a stepped crown element which selectively positions time indicia in accordance with the time indicated by the position of the stepped crown. In the present embodiment of the invention there are twelve different time indicia, one for each hour of the day. These indicia consist of pairs of die members 114, 115. 70 The lower die members are carried by a disk 116 carried by a sleeve splined to shaft 117. Each upper member of the pairs of die members is individually mounted upon a spring arm 118. The upper members are together held in place over 75

their companion lower members between a nut 119 and a hub of disk 116.

The lower end of shaft 117 carries a pinion 120 which is engaged by a rack 121 having at one end thereof projection 46 which is selectively positioned by the various steps upon the stepped crown 13 of the time recording key. When rack 121 is actuated by the introduction of the time recording key in its guide means 44, shaft 117 is rotated an amount sufficient to position the selected recording indicia opposite the edge of the record strip upon which the time is to be impressed. As illustrated in Fig. 17, the time is impressed just outside of the left-hand row of holes 93 in the record. In the present embodiment of the invention the indicia consist of male and female dies but any other form of marking or printing means may be employed.

After the proper pair of indicia has been selected by the cooperation of the stepped crown 13 and movement of rack 121, the printing operation is brought about. This is accomplished by the actuation of lever 124 when it is contacted by the end of stem 20 of the time recording key. Lever 124 is mounted upon pin 125 and it has a yoke connection with the sleeve carrying disk 116. Its clockwise movement (Fig. 16) causes it to raise disk 116, spring members 118 and hook 126. This hook engages and raises a hinged plate 127 normally held down by a spring 128. Cam surface 129 on hook 126 slides over ledge 130 until hook 126 is released from engagement with plate 127. This provides a sudden release of the restraining action of spring 128 and results in a quick application of force for raising disk 116 and indicia 115 thereon to bring about an imprinting operation. After this operation has been completed and the time recording key withdrawn from engagement with lever 124, spring 131 will ensure the dropping of the lever, hook 126 and indicia bearing disk members 116 and 118 to their normal positions (Fig. 16), and spring 132 will return hook 126 into engagement with plate 127.

Upon the withdrawal of the time recording key from its guide means 44, rack 121, together with the indicia bearing members and associated sleeve will be rotated to their normal positions by means of spring 133 and arm 134 (Fig. 14), which has connection with rack 121.

During the time recording operation, the indicia bearing wheel 116 is raised and the dies immediately beneath anvil 135 are brought together to impress a character upon the edge of the record. The upper and lower dies engage the upper and lower surfaces of the paper as spring member 118 carrying the upper die is carried into contact with the anvil.

Anvil 135 is supported upon fixed pivot 136, upon which it is adapted to be rocked, but when it is engaged by a spring element 118 during a time recording operation, its pivotal movement is restricted by the inner surface of guide means 85, so that for all purposes of time recording, anvil 135 is a relatively fixed member.

Anvil 135 performs the further function of imprinting a telltale character upon the record whenever the cover is opened or closed. The upper die of a pair of dies 137 for the telltale character 138 is carried by one of the spring elements 118 (Fig. 17), and the character is caused to be impressed upon the record whenever anvil 135 is rocked in a clockwise direction, as illustrated in Fig. 18. This is brought about whenever doubled-edge cam 139 engages nose 140 as the cover 75 is raised or lowered.

A station recording key of the type adapted to be used in the present watchman's system is illustrated generally in Figs. 18 and 19. This station recording key includes a pair of die members 142, 143, which are carried by a pair of spring members 144, 145. These spring members are normally held in an open position by means of a spring 146 (Fig. 19), cooperating with a pair of spring levers connected to the die carrying springs. Spring members 144, 145, are attached to a pin 147 carried by a casing 148 which is slidable into another casing 149. This latter casing is hinged by a pin 150 to a permanent support at a particular station. As the key is introduced into socket 83 and key guiding means 85 of the portable recording unit, a bar 151 is brought into engagement with lock 152 of the recording key and causes the same to shift longitudinally of casing 148 and the accompanying bringing together of spring members 144, 145 carrying the die members under the action of wedge 153. As indicated in Fig. 17, each station has a different station character and each station character is impressed by dies arranged at different distances from the ends of the recording keys. For an understanding of the present invention it will not be necessary to describe in more detail the construction of the station recording key. The same is fully disclosed in United States Patent No. 1,183,349, and United States Reissue Patent No. 30,143,93.

The watchman's portable recording unit is provided with means for preventing the making of a station record whenever the cover is raised from its closed position. This mechanism is illustrated in Figs. 13 and 15 particularly, and it includes lever 155 pivoted at 156 and having an arm carrying a projection 157 adapted to be interposed in the path of the station recording key 84. The lever 155 is so positioned as to be adjacent to the entry end of the station key receiving means 85 so that the station key may not be inserted within the casing when the projection is in its obstructing position, as illustrated in Figs. 13 and 14.

Arm 158 of lever 155 has a pair of laterally extending ears 162, 163, engaging link 159, which is pivotally connected to the cover 81 so that all movement of link 159 about its pivot effects movement of lever 155. Link 159 has a slot 160 and all movement of link 159 about its supporting pivot is controlled by a pin 161 fixed in the wall of the casing and engaging the slot. The slot is so designed that for the greater portion of its length it will not displace projection 157 from its obstructing position. For a short length of the slot near the cover of the casing the slot is diagonally disposed to give the link a quick movement as the cover nears or leaves its closed position. The closed position of the cover with link 159 in position to maintain projection 157 outside of the station key guide means 85 is illustrated in Fig. 15. Ears 162, 163, in extending laterally from arm 155 and engaging the opposite edges of link 159 serve to maintain positive 65 and definite control of projection 157 in reference to the cover. At no time can any one introduce a station recording key while the cover is removed from its closed position.

What is claimed is:

1. A watchman's recording unit comprising a casing, a record sheet contained therein, means within said casing for recording indications of time on said record sheet, a time key, a crown member in said key having steps corresponding 75

to different times, guide means in said casing for receiving said time key, means within said casing and controlled by the steps of said stepped crown for selecting indicia on said recording means for 5 recordation upon said record sheet, and means carried by said time key for effecting the recording of time impressions upon said record sheet, by the selected time indicia.

10 2. A watchman's recording unit comprising a casing, a record sheet contained therein, a cover for gaining access to said record sheet within the casing, means for advancing said record sheet, means for actuating said record sheet advancing means each time the cover is opened, and means controlled by a recording key for actuating 15 said record sheet advancing means each time the record key is inserted in the casing for making a record.

20 3. A watchman's recording unit for use in a multiple key watchman's time recording system, comprising a casing having an opening in a wall thereof for receiving a recording key, cover means for said casing, means in said casing for obstructing the entry of a recording key through 25 said opening when said cover is open, and means operated by said cover for maintaining said obstructing means in a non-obstructing position when said cover is closed.

30 4. A watchman's recording unit comprising a casing having an opening for receiving a recording key, a cover normally closing another opening by which access otherwise may be had to the contents of said casing, obstructing means adapted to be interposed in the first named opening 35 for preventing the insertion of a recording key, and means for interposing said obstructing means in said first named opening, said means being operated by said cover upon the initial movement of the cover from its closed position.

40 5. A watchman's recording unit comprising a casing having an opening for receiving a recording key, a cover normally closing another opening by which access otherwise may be had to the contents of said casing, obstructing means for 45 preventing the use of a recording key in said first named opening when the cover is moved from its closed position, and means controlled by said cover for moving the obstructing means to obstructing position during the initial opening 50 movement of the cover and for thereafter maintaining the obstructing position of said obstructing means for all movement of the cover beyond said initial movement.

55 6. In a watchman's recording system with a portable recording unit containing a record sheet and in which record sheet-carrying means is provided and arranged for advance by an inserted watchman's key which controls recording on the record sheet, the combination with said unit of time-imprinting means therein and control means for said time imprinting means, said control means being adapted for positioning by time-set means of a separate time controlled device.

65 7. In a watchman's recording system with a portable recording unit containing a record sheet and in which record sheet-carrying means is provided and arranged for advance by an inserted watchman's key which controls recording on the record sheet, the combination with said unit of 70 selectively positionable time-indicating indicia in said unit, means insertable in said unit for selectively positioning said time indicating indicia in accordance with time, and means associated with said insertable means for automatically setting the same in accordance with time.

8. In a watchman's recording system with a portable recording unit containing record sheet-carrying means and means for advancing said record sheet-carrying means by an inserted watchman's key which controls recording, the 5 combination with said unit of record time-imprinting means in said unit, control means for said time-imprinting means, said control means being adapted for positioning by time-set means of a separate time controlled device, and an element associated with said time-set means for effecting the printing by the prepositioned time-imprinting means.

10 9. In a watchman's recording system with a portable recording unit containing record sheet-carrying means and means for advancing said record sheet-carrying means by an inserted watchman's key which controls recording, the 15 combination with said unit of selectively positionable time-indicating indicia in said unit, a single 20 element insertable in said unit for selectively positioning said time indicating indicia in accordance with time, and means associated with said insertable means for actuating the selected one of said time-indicating indicia while the same 25 is being held in its selected position by said single element.

20 10. A watchman's recording unit comprising a casing, a record sheet contained therein, a cover for said casing, means in said casing for recording time characters upon said record sheet, means controlled by said cover for recording upon said record sheet and in relation to the time characteristics appearing thereon a record each time said cover is opened, and means also controlled 30 by said cover for advancing said record sheet in relation to said time characters recording means each time the cover is opened so as to present different portions of the record sheet opposite said cover-opening recording means for successive 35 recordings of successive openings of the cover.

35 11. In a watchman's recording system with a portable recording unit containing a record sheet and in which record sheet-carrying means is provided and arranged for advance by the insertion 40 of watchman's recording keys, the combination with said unit of means normally permitting insertion to said recording unit of said recording keys for advancing the record sheet and for recording thereon, a movable cover normally closing 45 an opening in said recording unit through which access may otherwise be had to the record sheet and record sheet-carrying means, means for preventing use of the watchman's recording keys for advancing the record sheet and which is 50 normally in a position permitting such use of the watchman's recording keys, and means controlled by said cover for displacing said last named means from normal position when said cover is displaced from its normally closed position and for maintaining the same in position to prevent the use of the watchman's recording keys so long as the cover remains displaced from its normally closed position.

55 12. In a watchman's recording system with a portable recording unit containing a record sheet and in which means is provided for enabling insertion to the recording unit of watchman's recording keys which control recording on the record sheet, the combination with said unit of 60 means for enabling insertion to said recording unit of said watchman's recording keys in the normal use of the same, a movable cover normally closing an opening in said recording unit, a movable element within said recording unit normally 65

in a position which permits the use of said recording keys in cooperation with said first named means to control recording on the record strip within said recording unit, and means controlled by said cover and having connection with said movable element to displace the same from its

normal position when the cover is displaced from its normally closed position so that when the cover is so displaced normal use of the watchman's keys is impossible.

LESLEY KENNEDY. 5
ALOIS BEYER.

CERTIFICATE OF CORRECTION.

Patent No. 2,119,637.

June 7, 1938.

LESLEY KENNEDY, ET AL.

It is hereby certified that error appears in the printed specification of the above numbered patent requiring correction as follows: Page 5, first column, lines 29 and 40, claims 4 and 5 respectively, after "unit" insert the words and comma for use in a multiple key watchman's time recording system,; and that the said Letters Patent should be read with this correction therein that the same may conform to the record of the case in the Patent Office.

Signed and sealed this 12th day of July, A. D. 1938.

Henry Van Arsdale,

Acting Commissioner of Patents.
